UNITED STATES PATENT OFFICE

FRANCIS R. BICHOWSKY, OF WASHINGTON, DISTRICT OF COLUMBIA, ASSIGNOR TO
FRIGIDAIRE CORPORATION, OF DAYTON, OHIO, A CORPORATION OF DELAWARE

THERMOSTAT FOR REFRIGERATING APPARATUS

Application filed December 29, 1928. Serial No. 329,111.

This invention relates to refrigerating apparatus and more particularly to a refrigerating system wherein the energy source is controlled by means of a thermostat having 5 an enclosed fluid medium acting upon a movable control member.

An object of this invention is to provide a refrigerating system which may be intermittently operated and which receives energy 10 for its operation from an energy source, said energy being controlled by an element with a flexible chamber receiving pressures from a fluid medium of such a character that the medium furnishes sufficient operating pressure at the low temperatures prevailing during the operation of the system and does not produce excessive pressures when the system is temporarily non-operative. Under certain 15 conditions the fluid medium may be separate 20 from the refrigerant of the system.

Further objects and advantages of the present invention will be apparent from the following description, reference being had to the accompanying drawing, wherein a 25 preferred form of the invention is clearly shown.

In the drawing

The figure is a view partly diagrammatic and partly in cross section of a refrigerating system embodying features of this invention.

A refrigerating system embodying features of this invention may comprise a compressor 20 which delivers compressed refrigerant to a condenser 21. The condenser 21 delivers condensed refrigerant to a receiver or storage reservoir 22. From thence the refrigerant may be delivered by means of a pipe 23 to an evaporator 24. In the 35 evaporator 24 the refrigerant is evaporated and returns to the compressor 20, preferably through a pipe 25 delivering into the crank-case of the compressor. In this particular embodiment, the system may be of the expansion type, in which case the liquid refrigerant from the pipe 23 passes to an automatic expansion valve 26 wherein the refrigerant is automatically expanded to a predetermined low pressure. The expanded 40 refrigerant may then pass through a pipe 27

to the evaporator, for instance to the inner coils 28. The coils 28 may form a freezing zone for the reception of trays for forming ice cubes and the like. After passing through the inner coils 28 the refrigerant 55 may pass to the outer air cooling coils 29 and from thence to the pipe 25 and the compressor 20. If desired, the automatic expansion valve 26 may be provided with an artificial atmosphere formed by the tube 30 and the bulb 31 so that the atmosphere on one side of the diaphragm in the expansion valve 26 may be kept substantially constant, since the bulb 31 may be placed in the space to be refrigerated. 65

The refrigerating system may be intermittently operated, for instance, by being intermittently driven by a motor 32, which may be connected by the belt 33 with a flywheel 34 of the compressor 20. The motor 32 may be 70 started and stopped by means of a snap switch 35 which is operated by a flexible chamber 36 connected by tubing 37 with a thermostatic bulb 38 placed adjacent to the evaporator 24. A volatile fluid in the bulb 75 38 actuates the flexible chamber 36, so that it opens and closes the electric contacts 39 for making and breaking the electric circuit 40 which supplies energy to the motor 32. This system, as thus far described, may be, 80 though not necessarily, of the type described in the application of Harry B. Hull, Serial No. 183,480, filed April 13, 1927, now Patent 1,883,920 granted Oct. 25 1932 which is merely referred to as an example of a refrigerating system which may be modified to 85 embody features of this invention. It is obvious, however, that other systems may embody features of this invention. The snap switch may be, though not necessarily, of the type shown in the said application of Harry B. Hull. 90

It is to be seen that the snap switch mechanism is generally of a type which embodies a pivoted arm 50, and this arm may be fulcrumed for instance at the point 51 and may receive the actuating force of the flexible chamber 36 for instance by a knife edge member 52. The other end of the arm may be provided with the snap mechanism 53 and with 100

the electrical contacts 39. In this particular embodiment, an adjustable pointed screw 54 acts on the cup-shaped end member 55 of a spring 56. The other end of the spring 56 5 may be provided with a cup-shaped member 57 engaging with stationary pointed member 58. As the end of the arm 50 swings up and down, the alignment of the members 58 and 54 is such that a snap action is produced by virtue of the compression of the 10 spring 56 and the alignment of the members 58, 54 causing the spring to reach an intermediate point of maximum compression. Other adjustments, such as the spring 60 having 15 an adjustable connection 61 with the arm 50, together with the adjustment 54 enable the snap switch to be so adjusted that the motor is started and stopped to produce predetermined high and low pressures in the 20 vicinity of the evaporator 24.

In domestic refrigerators and the like the predominating temperatures in the evaporator at present hover around -10° C. (14° F.). Thus it is seen that if the thermostatic bulb 38 should be filled with pure sulphur dioxide, the pressure acting on the flexible chamber 36 would be 0 lbs. gauge. It thus would seem that, at the temperatures when the thermostat should be most sensitive, that actually 25 the thermostat is providing the least amount of pressure. Should the thermostatic bulb be filled with methyl chloride, the pressure acting on the flexible chamber 36 would be sufficient at temperatures around -10° C. 30 (14° F.). However, should the system remain idle for a long period of time, as during the vacancy of the residence, during transportation of the system, or the like, the temperatures acting on the bulb 38 might rise to 35 some temperature such as 40° C. (104° F.). At this temperature, the pure methyl chloride would exert a pressure of 112 lbs. gauge. This is such an excessive pressure that it has a tendency to distort the members of the 40 flexible chamber 36 and possibly the knife edge contact of the member 52 which is close to the fulcrum point 51.

In order to overcome these various objections, fluids may be so chosen, according to this invention, that they may be mutually soluble, non-reacting and at least two may be so chosen that one has a pressure above and the other has a pressure below the pressure necessary to operate the movable control member at the predominant operating temperature of the refrigerating system. Thus an equal mixture of sulphur dioxide and methyl chloride may be made. In a preferred embodiment, the proportions of these substances may be in the ratio of one mol of sulphur dioxide to one mol of methyl chloride. Such a mixture exerts a pressure of about 5 lbs. at -10° C. (14° F.) which is 55 sufficient in this case to operate the snap

switch. Should the temperature rise to 40° C. (104° F.), this mixture would exert only about 90 lbs. gauge which would be insufficient to distort the mechanism of the type herein disclosed. Another mixture which is suitable under these conditions is methyl chloride and normal butane in the proportions of two parts of methyl chloride and one part of normal butane. Such a mixture has about 5 lbs. gauge pressure at -10° C. 70 (14° F.) and only 60 or 70 lbs. at 40° C. (104° F.). Various other mixtures in accordance with the principles herein disclosed may be chosen. Some of the preferred substances for making these mixtures are at least two of the following: sulphur dioxide, methyl chloride, isobutane and the pair ammonia and methylene. In general, it is necessary to obtain at least two mutually soluble 75 and non-reacting fluids, or liquids, in which one has the pressure above, and the other a pressure below, that necessary to operate the movable control member at the predominant operating temperature. The exact desired pressure may be obtained by varying the proportions of the substances so mixed. 80

While the form of embodiment of the invention as herein disclosed constitutes a preferred form, it is to be understood that other forms might be adopted, all coming within the scope of the claims which follow. 85

What is claimed is as follows:

1. In a refrigeration system, control means therefor, said control means comprising a thermostat element containing a mixture of at least two mutually soluble, non-reacting fluids having pressures one above and the other below the pressure necessary to operate said movable control member at a predominant operating temperature of the refrigerating system. 100

2. In a refrigeration system, control means therefor, said control means comprising a thermostat element containing a mixture of at least two mutually soluble, non-reacting fluids having pressures one above and the other below the pressure necessary to operate said movable control member at the lower operating temperature limit of the refrigerating system. 110

3. In a refrigeration system, control means therefor, said control means comprising a thermostat element containing a mixture of sulphur dioxide and methyl chloride. 115

4. In a refrigeration system, control means therefor, said control means comprising a thermostat element containing a mixture of sulphur dioxide and methyl chloride in the proportions of one mol of sulphur dioxide and one mol of methyl chloride. 125

5. In a refrigeration system, control means therefor, said control means comprising a thermostat element containing a mixture of at least two mutually soluble, non-reacting 130

fluids having pressures one above and the other below the pressure necessary to operate said movable control member at a predominant operating temperature of the refrigerating system, said fluid medium containing at least two of the following substances, sulphur dioxide, methyl chloride, normal butane, isobutane and the pair, ammonia and methylamine.

- 10 6. In a thermostatic control means for refrigerating apparatus in which in order to operate the control means a volatile liquid is used having an insufficient vapor pressure at the low operating temperatures to properly actuate the control means, the method of correcting the vapor pressure characteristics by adding a second volatile liquid having a higher vapor pressure in a quantity limited so as to prevent the occurrence of excessive vapor pressures at high temperatures when the apparatus is idle, but providing an increased vapor pressure at operating temperatures.
- 15 20 25 In testimony whereof I hereto affix my signature.
